UNITED STATES PATENT OFFICE.

ELMER J. MERCIL, OF OAK PARK, ILLINOIS.

ELECTROPLATING APPARATUS.

Application filed January 26, 1924. Serial No. 688,670.

To all whom it may concern:

Be it known that I, ELMER J. MERCIL, a citizen of the United States, residing at Oak Park, in the county of Cook and the State of Illinois, have invented a certain new and useful Improvement in Electroplating Apparatus, of which the following is a full, clear, concise, and exact description.

My invention relates to electroplating apparatus of a class employing tumbling barrels which are turned or otherwise moved in the electrolyte contained in the tanks. These tumbling barrels are usually equipped with sievelike encompassing walls having portions which are removable for the insertion and removal of the objects that are plated in the apparatus. The cathodes are carried by and within the tumbling barrels and have contact with the electrolyte therein. Anodes are contained on the exteriors of the barrels and are carried by the tanks. Hitherto the metallic bearings which supported the barrels had electrical connection with the cathodes and were, therefore, in the path of the tank current and received thereon plating deposits which, in the course of time, would accumulate to such an extent as to bind the barrels at their bearings to prevent free movement thereof.

In accordance with one feature of my invention the metallic bearings for the barrels are electrically separated from the cathodes so as to be excluded from the tank current thereby to be free of any plating action thereon.

The invention has, as another of its characteristics, the provision of switching means and circuit connections whereby when the barrels are removed from the tanks the tank circuits are opened and when the barrels are restored to the tanks, the tank circuits are closed.

The invention will be more fully explained in connection with the accompanying drawings showing the preferred embodiment thereof and in which Fig. 1 is a sectional view on line 1—1 of Fig. 2 with parts shown in elevation; Fig. 2 is a plan view of the structure shown in Fig. 1; Fig. 3 is a vertical sectional view through the barrel and contiguous portions with parts being broken away and other parts being shown in elevation; Fig. 4 is a sectional view on line 4—4 of Fig. 1; Fig. 5 is a sectional view on line 5—5 of Fig. 3 but on a smaller scale; Fig. 6 is an end view illustrating a part of

the switching mechanism by which the cathodes in the barrel are brought into and out of the tank circuit, according to the location of the barrel; and Fig. 7 is a sectional view on line 7—7 of Fig. 3 with parts broken away and other parts shown in elevation.

Like parts are indicated by similar characters of reference throughout the different figures.

The electroplating tank 1 includes any suitable form of liquid electrolyte 2. The anodes 3 which are to supply the metal or material to the objects to be plated are hung upon metallic bus rods 4 which are supported upon the tank in position to permit these anodes to be sufficiently inserted within the electrolyte. These bus rods are connected in series by another metallic rod 5, the three metallic rods being connected by a conductor 6 with the positive pole of the electroplating generator or other source of current, this source furnishing direct current unless the electrolytic cell itself is capable of rectifying alternating current.

The tumbling barrel may be of any suitable form and mounted in any suitable way. In the embodiment of the invention illustrated this tumbling barrel is six sided, being surrounded by a sievelike encompassing wall 8 and having one of its sides detachably applicable with the aid of the fastening bolts 9 as illustrated most clearly in Figs. 1, 2, 3 and 5. The anode element composed of bars 3 is subdivided into two rows which are sufficiently spaced apart to receive the tumbling barrel therebetween. The cathode element is desirably in the form of eight T shaped metal blocks 10 which are carried by the wooden end walls 11 of the barrel. These cathode blocks project into the interior of the barrel so as to have contact with the electrolyte.

In the embodiment of the invention shown, the barrel is mounted to turn upon a horizontal axis but, as is well known to those skilled in the art, tumbling barrels are otherwise mounted to move within the electrolyte of plating tanks and I do not therefore wish to limit myself to the rotation of the barrel upon a horizontal axis.

In the embodiment of the invention illustrated the end walls 11 of the barrel which are preferably of wood, carry metallic stub shafts 12—13 which project outwardly beyond the same. A metallic bushing 14 is applied by means of screws 15 to and upon

the outside of one of the end walls 11. An insulating bushing 16 surrounds the metallic bushing 14, another metallic bushing 17 surrounds the insulating bushing 16 and is secured to the same end wall 11 that carries the bushing 14 by means of the screws 18. An insulating bushing 19 surrounds the metallic bushing 17 and is housed by the bushing 20, bushings 19 and 20 being secured to the adjacent end walls 11 of the barrel by means of screws 21. The shaft 12 is preferably in keyed connection with the inner most metallic bushing 14 so that when the shaft is turned the barrel will be turned positively, power being applied to the barrel by a suitably turned shaft 22 which is brought into connection with the shaft 12 by means of the complemental clutch members 23 and 24 respectively carried by the shafts 22 and 12.

The revoluble unit which includes the elements 12, 14, 16, 17 and 19 is journaled to rotate in a metallic bearing 25 which is carried by the lower end of a hanger 26 having leveling projecting ends 27 which rest upon the brackets 28 which are carried by the adjacent end walls of the tank 1 so as to overlie the electrolyte. By the construction described, the metallic bearing 25 is so thoroughly insulated and electrically separated from the cathode element as to be totally excluded from the tank circuit and will therefore be free of the electro-plating action thereon and the accumulation of deposits which hitherto obtained to such an extent as to interfere with the proper movements of the plating barrels. The other stub shaft 13 has a flanged inner end which is assembled at the other end 40 of the barrel with the adjacent barrel end wall 11 of wood by the screws 29. A flanged sleeve 30, of insulation, houses the metallic stub shaft 13 and is placed in fixed relation therewith by means of screws 31 which pass into the adjacent wooden end wall 11 of the barrel.

The cathodes 10 at the driven end of the barrel are similarly connected in the plating circuit by the non-rotating slip contact body 32 which, at this end of the barrel, is in the form of a ring which surrounds the stub shaft 12. This ring is held against the metallic sleeve 17 that is connected with these cathodes by the spring 33. A stiff terminal rod 34 is screwed into the ring 32 and passes upwardly through the insulating sleeve 35 that passes through the adjacent metallic hanger 26 for the metallic bearing 25 made preferably of metal. The upper end of the terminal rod 34 is outwardly bent at right angles to be engageable with and between the jaws of the metallic terminal clip 36 with which the negative generator conductor 37 is connected.

The cathodes 10 at the other end of the barrel are similarly connected in the plating circuit by the non-rotating slip contact body 38. This body is held against the metallic shaft 13 that is connected with these cathodes, by the spring 39. A stiff terminal rod 40 is screwed into the body 38 and passes upwardly through the insulating sleeve 41 that passes through the adjacent metallic hanger 26 for the metallic bearing 25 in which the relatively fixed elements 13 and 30 turn. The upper end of the terminal rod 40 is outwardly bent at right angles to be engageable with and between the jaws of the metallic terminal clip 42 with which a second negative generator conductor 43 is connected. The cathodes 10 at both ends of the barrel are thus connected with the negative terminal of the plating generator whose positive terminal is connected with the anodes by the conductor 6, as hitherto described. The barrel may be raised and the cathode terminals 34, 40 carried thereby at the same time separated from their complemental clips 36, 42 to open the plating circuit whenever the barrel is to be emptied of its contents or is to be loaded with objects to be plated. The plating circuit is automatically restored when the barrel is lowered into functioning position.

It is obvious that changes may be made without departing from the spirit of my invention.

Having thus described my invention I claim as new and desire to secure by Letters Patent the following:—

1. In an electroplating apparatus, the combination with a tank containing an electrolyte; an anode element in said electrolyte; a barrel within the tank and in communication with its interior to receive electrolyte therefrom; a cathode element carried by said barrel and in contact with the electrolyte therein; a metallic bearing structure within the tank and upon which the barrel is mounted to turn, this bearing structure being mounted to be movable to permit the barrel to be placed in accessible position; a terminal for the cathode element carried by the bearing structure; a circuit terminal complementary to the aforesaid terminal and engageable thereby when the barrel and its bearing structure are in place within the electrolyte and from which complemental circuit terminal the cathode terminal is separable when the barrel is adjusted to be accessible; contacts in slipping engagement interposed between the cathode element and its aforesaid terminal; and insulation between said cathode element and said bearing structure to substantially exclude the bearing structure from the plating circuit.

2. In an electroplating apparatus, the combination with a tank containing an elec-

- trolyte; an anode element in said electrolyte; a barrel within the tank and in communication with its interior to receive electrolyte therefrom; a cathode element carried by said barrel and in contact with the electrolyte therein; a metallic bearing structure within the tank and upon which the barrel is mounted to move, this bearing structure being mounted to be movable to placed in accessible position; a terminal for the cathode element carried by the bearing structure; and a circuit terminal complementary to the aforesaid terminal and engageable thereby when the barrel and its bearing structure are in place within the electrolyte and from which complementary circuit terminal the cathode terminal is separable when the barrel is adjusted to be accessible. 40
- 5 permit the barrel to be placed in accessible position; a terminal for the cathode element carried by the bearing structure; a circuit terminal complementary to the aforesaid terminal and engageable thereby when the barrel and its bearing structure are in place within the electrolyte and from which complementary circuit terminal the cathode terminal is separable when the barrel is adjusted to be accessible. 45
- 10 15 20 25 30 35 40 45 50 55 60 65 70
3. In an electroplating apparatus, the combination with a tank containing an electrolyte; an anode element in said electrolyte; a barrel within the tank and in communication with its interior to receive electrolyte therefrom; a cathode element carried by said barrel and in contact with the electrolyte therein; a bearing structure within the tank and upon which the barrel is mounted to turn, this bearing structure being mounted to be movable to permit the barrel to be placed in accessible position; a terminal for the cathode element carried by the bearing structure; a circuit terminal complementary to the aforesaid terminal and engageable thereby when the barrel and its bearing structure are in place within the electrolyte and from which complementary circuit terminal the cathode terminal is separable when the barrel is adjusted to be accessible; and contacts in slipping engagement interposed between the cathode element and its aforesaid terminal. 65
3. In an electroplating apparatus, the combination with a tank containing an electrolyte; an anode element in said electrolyte; a barrel within the tank and in communication with its interior to receive electrolyte therefrom; a cathode element carried by said barrel and in contact with the electrolyte therein; a bearing structure within the tank and upon which the barrel is mounted to move, this bearing structure being mounted to be movable to permit the barrel to be placed in accessible position; a terminal for the cathode element carried by the bearing structure; a circuit terminal complementary to the aforesaid terminal and engageable thereby when the barrel and its bearing structure are in place within the electrolyte and from which complementary circuit terminal the cathode terminal is separable when the barrel is adjusted to be accessible; and contacts in slipping engagement interposed between the cathode element and its aforesaid terminal. 60
4. In an electroplating apparatus, the combination with a tank containing an electrolyte; an anode element in said electrolyte; a barrel within the tank and in communication with its interior to receive electrolyte therefrom; a cathode element carried by said barrel and in contact with the electrolyte therein; a bearing structure within the tank and upon which the barrel is mounted to move, this bearing structure being mounted to be movable to permit the barrel to be placed in accessible position; a terminal for the cathode element carried by the bearing structure; a circuit terminal complementary to the aforesaid terminal and engageable thereby when the barrel and its bearing structure are in place within the electrolyte and from which complementary circuit terminal the cathode terminal is separable when the barrel is adjusted to be accessible; and contacts in slipping engagement interposed between the cathode element and its aforesaid terminal. 55

In witness whereof, I hereunto subscribe my name.

ELMER J. MERCIL.
